UNITED STATES PATENT OFFICE

108,150

DESIGN FOR A COMBINED VANITY UNIT AND HANDBAG

Pedro Bautista, Brooklyn, N. Y.

Application January 11, 1937, Serial No. 67,607

Term of patent 7 years

To all whom it may concern:

Be it known that I, Pedro Bautista, a citizen of the United States, residing at Brooklyn, in the county of Kings and State of New York, have invented a new, original, and ornamental Design for a Combined Vanity Unit and Handbag, of which the following is a specification, reference being had to the accompanying drawings, forming part thereof.

bined vanity unit and handbag, showing my new design.

Figure 2 is a front perspective view thereof with the closure flap raised.

I claim:—

The ornamental design for a combined vanity unit and handbag as shown.

PEDRO BAUTISTA.
